UNITED STATES PATENT OFFICE.

ELROY A. CHASE, OF NORTHFIELD, VERMONT.

SCROLL WHEEL.

Application filed July 12, 1926. Serial No. 121,765.

This invention relates to a grinding wheel having grinding members of a general scroll-like form. The scroll type of wheel has been heretofore commonly used for grinding flat surfaces on blocks of granite and other similar material and it is the general object of my invention to improve the construction of such scroll wheels to the end that they may be more effectively adapted to certain 10 special grinding operations.

It is more specific object of my invention to provide a scroll wheel which will be particularly adapted to grinding blocks of granite having surfaces which are curved in 15 one section and straight or flat in a section perpendicular thereto. Such blocks are commonly but somewhat inaccurately termed "oval tops" in the stone polishing trade.

In grinding such curved surfaces, the 20 grinding wheel makes only a line contact with the stone and the wear of the wheel is quite different from that which occurs in grinding a flat surface. The amount of 25 surface to be ground with line contact is substantially the same at all radial distances from the axis of the wheel, while the area of the grinding surface of the wheel commonly increases with the radial distance from the axis and the outer portions of the 30 wheel are also rotating at much increased speed.

For this reason, "oval tops" have commonly been produced by other and more expensive methods such as the use of surface cutters. Whenever any one attempted 35 to use the ordinary scroll or ring wheel on oval top work, the wheel had a strong tendency to become concave or dished at the center and the work was apt to be correspondingly rounded or convex where it should be 40 flat.

It is a further object of my invention to provide a scroll wheel so designed as to substantially equalize the wear at different 45 radial distances from the axis of the wheel, thereby preserving the flat grinding surface of the wheel. To the attainment of this object, I provide a design for the scroll members which substantially increases the area 50 of grinding surface toward the center of the wheel, offsetting the greater circumference and higher speed at the periphery.

A further feature of the invention relates 55 to the provision of a series of pockets in the inner walls of scroll members of the type

described, by which provision the efficiency of the wheel is still further increased.

My invention further relates to arrangements and combinations of parts which will be hereinafter described and more particularly pointed out in the appended claims.

Preferred forms of the invention are shown in the drawings in which

Fig. 1 is a bottom view of a scroll wheel embodying one form of my invention;

Fig. 2 is a top or plan view thereof;

Fig. 3 is a side elevation of the wheel shown in Figs. 1 and 2, and

Fig. 4 is a bottom view of a modification.

Referring to Figs. 1 and 3, I have shown a small scroll wheel preferably of cast iron, and comprising two scroll members 10 connected by a cross bar 11 and also by spots or tying elements 12. The cross bar 11 is provided with ears 13 adapted to receive a 75 rocking member 14 pivoted on a cross pin 15 in the end of a drive shaft 16.

The grinding wheel W thus has a swivel connection with the drive shaft 16 and is held against the stone S by the direct pressure of the drive shaft against the ears 13. The wheels may be removed and replaced by merely raising the drive shaft out of the open bearings in the ears 13.

The scroll members 10 are of a special 85 shape and construction which will now be described. The extreme outer end portion of each member 10 is substantially concentric with the axis of the wheel between the points *a* and *b* (Fig. 1), or for about a 90 quarter of the circumference. The provision of these circular outer portions has been found very desirable for use on oval top work in which reverse curves are frequently encountered, as the cylindrical outer 95 surfaces prevent the bumping or jarring action which would otherwise occur when the edges of the scroll wheel encountered a reversed curve portion of the surface.

Each grinding element 10 is also gradually increased in effective width as the scroll approaches the axis of the wheel. The object of this increase in width, as previously pointed out, is to equalize the wear of the wheel when grinding a curved surface in 105 which there is only line contact, and in which the wheel surface area operative at a given point on the line of contact otherwise varies directly with the distance from the axis. By increasing the width of the grind- 110

ing surface as it approaches the center, this variation in grinding action is substantially offset and a wheel is produced which will wear evenly and preserve its flat grinding face even when used on oval top work with line contact only.

I further increase the efficiency of my improved grinding wheel by providing a series of pockets or serrations 17 on the inner faces of the grinding members 10. The outer wall 18 of each pocket is preferably substantially concentric with the axis of the wheel W and this construction facilitates the feed of the abrasive under the scroll-shaped grinding members. A grinding wheel constructed as above described has been found very effective for the purposes indicated and is adapted to take the place of the much more expensive surface cutting operation which has been commonly used for producing curved or oval top surfaces.

In Fig. 4, I have shown a wheel having a single continuous scroll member but otherwise of the construction previously described. This wheel may also be provided with pockets as in the form shown in Figs. 1 to 3.

Having thus described my invention and the advantages thereof, I do not wish to be limited to the details herein disclosed otherwise than as set forth in the claims, but what I claim is:—

1. A wheel for grinding stone having a scroll-shaped grinding member, the grinding surface of which is gradually increased throughout the length of the scroll as said scroll member approaches the axis of the wheel.

2. A wheel for grinding stone having a scroll-shaped grinding member in which the

average effective width of grinding surface is constantly increased throughout the length of the scroll toward the axis of the work.

3. A wheel for grinding stone having scroll-shaped grinding members in which the grinding surface of said members is increased in width throughout the length of the scroll toward the axis of the wheel, and in which the inner side faces of said members are serrated.

4. A wheel for grinding stone having a scroll-shaped grinding member, the grinding surface of which is gradually increased throughout the length of the scroll as said scroll member approaches the axis of the wheel, and in which wheel the extreme outside portion of said member forms substantially the segment of a cylinder.

5. A wheel for grinding stone having scroll-shaped grinding members, the grinding surfaces of which are gradually increased throughout the length of the scroll as said scroll members approach the axis of the wheel, and in which pockets are provided in the inner faces of said members, the outer walls of said pockets being substantially concentric with the axis of said wheel.

6. A wheel for grinding stone, comprising a plurality of independent scroll shaped grinding members tied together by a cross-bar, the grinding surfaces of each of said members being gradually increased throughout the length of the scroll as the members approach the axis of the wheel formed by the members.

In testimony whereof I have hereunto affixed my signature.

ELROY A. CHASE.
